UNITED STATES PATENT OFFICE.

VERNE F. DEATS, OF TIFFIN, OHIO.

JAR-LIFTER.

1,359,968.

Specification of Letters Patent. Patented Nov. 23, 1920.

Application filed October 25, 1919. Serial No. 333,308.

To all whom it may concern:

Be it known that I, VERNE F. DEATS, a citizen of the United States, residing at Tiffin, in the county of Seneca and State of Ohio, have invented certain new and useful Improvements in Jar-Lifters, of which the following is a specification.

This invention relates to a jar lifter and has for its principal object the production 10 of a simple and efficient device which may be easily attached or detached from around the outer surfaces of hot jars.

Another object of this invention is to provide a jar lifter which may be manufactured 15 at the smallest possible cost.

A still further object of this invention is to provide a resilient wire, one end of which is fixedly attached to a stick and means provided upon the other end for holding said 20 wire securely around a jar.

With these and other objects in view, this invention consists of certain novel combinations, constructions and arrangement of parts as will be hereinafter more clearly 25 described.

In the drawings:—

Figure 1 is a perspective view of the device.

Fig. 2 is a section taken through the stick 30 portion of the device.

Fig. 3 is a detailed fragmentary view partly in section showing how the resilient arm is attached to the stick.

By referring to the accompanying drawings 35 by numerals it will be seen that 1 designates a stick upon which is provided the resilient arm 2. Upon the rear face of the stick is provided a slot 3 into which the end 4 of the arm 2 is held by means of a 40 staple 5. This arm 2 is bent at substantially right angles at 3 and terminates in the eye portion 4 as is clearly shown in Fig. 1 of the drawing.

A resilient wire 6 is fixedly attached to the 45 stick 1 by means of passing into said stick a spaced distance as is clearly shown at 7 in Fig. 2 of the drawings. This wire then passes through the eye 4 of the resilient arm 2 and passes around to the other side of the 50 stick 1, that is the side opposite into which the end of the wire is attached to the stick. Upon the latter side of the stick 1 is provided the bracket 8 which extends along the side of the stick 1 for a distance and is then 55 bent at substantially right angles. At each

end of the angular bracket 8 are provided eyes. Through one of these eyes passes the eye screw 9 as is shown in Fig. 1.

The resilient wire 6 passes through the eye 4 and through the eye provided upon the free end of the bracket 8 and then through the eye provided in the screw 9. Another eye screw is provided a spaced distance above the eye 9 as is indicated at 10 in Fig. 1 of the drawings. The resilient wire 6 terminates 65 in the eye 11 so as to receive the ring 12.

From the above description it will be seen that the operation of the device is as follows: When the drawer is in this position it will be seen that by pulling upwardly on the 70 ring 12 and thereby causing the resilient wire 6 to pass up through the eyes 9 and 10 the same will be forced tightly around the outer periphery of the jar. When the wire 6 is pulled it will be seen that the eye 75 portion 4 of the resilient arm 2 will be pulled toward the stick 1 so that when the wire 6 is released, the resilient action of the arm 2 will cause the wire 6 to be pulled back through the eyes 9 and 10, thereby 80 making the loop through which the jar is positioned large enough to free the lifter from the same. From the construction shown in Fig. 3 it will be seen that the end 85 of the resilient arm 2 passes through the stick 1 and is fitted within a longitudinally extending slot so that the end thereof may be fixedly held within the slot by means of the staple 5 so that the usually sharp end of the wire will be prevented from cutting in 90 any way the operator of the device. By referring further to Fig. 2 it will be seen that the end of the resilient wire 6 is also passed into the stick 1 so as to be fixedly held therein and be at the same time prevented from injuring the operator. 95

From the above description it will be seen that I have produced a simple and efficient jar lifter which is adapted to be constructed of sheet material and to consist of a minimum number of parts. It will also be seen that the device is easily constructed and therefore may be cheaply manufactured. I do not intend to limit myself to the peculiar construction as shown, only inasmuch as set 100 forth in the accompanying claims.

What I claim as new is:—

1. In a device of the class described comprising a stick, a resilient arm, a resilient wire fixedly attached adjacent the bottom 110

end of said stick, said wire passing through an eye provided upon the free end of said resilient arm, a bracket fixedly attached to said stick, said wire passed through an opening in said bracket.

2. A device of the class described comprising a stick, a resilient arm, one end of said resilient arm, fixedly attached a spaced distance from one end of said stick, a bracket fixedly attached to said stick, the free end of said bracket provided with an eye, said wire passed through an opening in said eye, and means provided for holding said wire in a large looped position so that a jar may be 15 passed through said loop.

3. In a device of the class described, the combination of a stick with a resilient arm, said arm fixedly attached to said stick, said arm extending at right angles from said 20 stick and bent so as to extend substantially parallel therewith, said arm terminating in an eye, a resilient wire one end of said resilient wire fixedly attached to said stick, a bracket provided upon said stick, the free 25 end of said bracket provided with an eye, a plurality of screws provided upon said stick, said resilient wire passed through the above mentioned eye whereby the free end of said resilient wire may be pulled so as to cause

same to fit snugly around the outer periphery 30 of a jar for lifting same.

4. In a device of the class described, the combination of a stick, with a resilient arm, one end of said resilient arm passed through said stick and to be bent at right angles so 35 as to fit within a slot provided within said stick, a staple provided for fixedly holding said end within said slot and to said stick, said resilient arm extending at right angles from said stick and bent so as to extend substantially parallel therewith, the other end of said arm terminating in an eye, a bracket provided upon said stick, said bracket being bent at right angles so as to 40 extend away from said stick, the outwardly 45 extending portion provided with an eye, said outwardly extending portion adapted to be twisted so as to allow said wire to pass within the eye provided at the free end of said resilient arm without buckling and with 50 the least possible friction.

In testimony whereof I affix my signature in presence of two witnesses.

VERNE F. DEATS.
